UNITED STATES PATENT OFFICE.

ADOLPH WIDMER AND SAMUEL WIDMER, OF PATERSON, NEW JERSEY; SAID ADOLPH WIDMER EXECUTOR OF SAID SAMUEL WIDMER, DECEASED.

SHUTTLE FOR LOOMS.

1,038,048.

Specification of Letters Patent. Patented Sept. 10, 1912.

Application filed November 26, 1909, Serial No. 530,067. Renewed February 20, 1912. Serial No. 678,957.

To all whom it may concern:

Be it known that we, ADOLPH WIDMER and SAMUEL WIDMER, citizens of the United States, residing in Paterson, Passaic county,

5 New Jersey, have invented a certain new and useful Improvement in Shuttles for Looms: and we do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 This invention relates to loom shuttles and particularly to the means for supporting therein the quill or bobbin. In one class of such shuttles, notably for narrow-ware looms, the quill is arranged on an axial support which is secured in the shuttle at both ends and is rotatable on its support so as to discharge the thread; usually this support takes the form of a pin which fits into a hole in the shuttle at one end and is suitably held at the other, and as the pin is bodily removable from the shuttle it is often lost and besides makes necessary some experience and skill in the assembling and disassembling of the parts.

20 Our object in the present invention is to provide a shuttle in which the axial support for the quill remains at all times attached to the shuttle body.

A further object is so to arrange and construct the parts that when the shuttle is in use the axial support for the quill will remain positively in proper position and not be likely, for instance, to become sufficiently displaced so as to project and possibly cause 25 damage to the goods being woven.

To this end our invention consists in providing in one of two opposed walls in a shuttle body, as in the bow thereof, a recess entering said wall from one side thereof and 30 opening toward the other wall, together with an axial support for a quill, which support projects from the other of said walls and has its free end normally engaged in, but movable laterally of the axis of said support out of, said recess.

Referring to the accompanying drawing, in which the invention is fully shown, Figure 1 is a front elevation of the improved shuttle, a part of the body thereof being 35 broken away to reveal a detail of the quill-

supporting means; Fig. 2 is a horizontal sectional view on line $x-x$ of Fig. 1; Fig. 3 is a vertical sectional view on line $y-y$ of Fig. 1, looking toward the left; Fig. 4 is a similar view on line $z-z$, looking toward the right; and, Fig. 5 illustrates a detail.

a designates the shuttle body, the same having the usual bow b and a wire guard c to keep the quill from engaging the shed.

d is the quill and e the usual tension-device adapted to bear frictionally against the quill, operating as a brake thereon.

The axial support for the quill is constructed and the manner of mounting it is as follows: f is a pin or spindle, formed, say, of wire, being straight throughout, except at one end, which is turned off substantially at right angles, as at g . This pin forms the said axial support and onto it the quill may be placed, as shown in Fig. 1, so as to rotate 75 freely.

The two opposed walls h , h' of the shuttle-body support the pin f in the usual position, *i. e.*, parallel with the base of the shuttle-body and are constructed for that purpose 80 as follows: The wall h has an elongated recess or groove i extending perpendicular to the base of the shuttle-body. Over this groove is secured, as by screws j , one arm of an angle-plate k , the other arm of which 85 is secured in like manner against the face of the base of the shuttle-body which is within the bow. At the end of the groove which is the farther from the base the plate is formed with a hole l . Before securing 90 the plate in position the end g of the pin is passed through this hole, whose diameter is slightly larger than the cross-section of the pin. When the plate is then secured, the plate and groove form a bearing for the 95 part g of the pin, in which said part g fits rather snugly; the pin may then be moved in the bearing from a position in which it lies in the longitudinal axis of the shuttle, as indicated by the dot-and-dash lines in 100 Fig. 2, to the position indicated by full lines in the same figure. When moved on the part g as an axis the body portion of the pin will follow a plane which is perpendicular to said axis, unless pressure is applied 105 in the direction of the length of said axis, as toward the base of the shuttle, the pin being somewhat elastic so that it will yield to such pressure but return to its normal disposition when the pressure is removed.

110

Entering the wall h' from one side thereof and open toward the wall h is a recess or groove m . The entrance end of this recess or groove is somewhat out of the plane in which the body portion of the pin f tends to move while its other or closed end is more or less in said plane; this may be accomplished either by forming the groove oblique to said plane, as at n , or by forming its closed end in offset disposition to its entrance portion, as at o . The pin is sufficiently long so that its free end will be received by said groove or recess m when the pin occupies the position indicated by dot-and-dash lines in Fig. 2. The pin being in the position shown by full lines in Fig. 2, the quill is slipped onto the same. The pin, carrying the quill, is then turned on its axis g toward the position indicated by dot-and-dash lines in Fig. 2 its free end being pressed toward the base of the shuttle until it enters and finally seats at the closed end of the recess m . In this position it will be held by virtue of its elasticity, until, when the pin is to be removed, pressure is again applied to clear its free end from the recess.

We do not wish to be limited to the de-

tails of construction herein shown and described, what we claim being:

The combination of a shuttle body having opposed walls and a recess in one of said walls entering the same from one side thereof and open toward the other wall, and an elastic pin having a substantially straight body-portion and one end turned off at an angle to said body-portion and journaled in the other wall, whereby said pin may swing on said turned-off end thereof as a pivot, the free end of said body-portion of the pin being engageable in said recess and the entrance end of said recess being disposed farther than the other end of said recess from the plane in which the body-portion of the pin swings when the latter is clear of the recess, substantially as described.

In testimony, that we claim the foregoing, we have hereunto set our hands, this 23rd day of November, 1909.

ADOLPH WIDMER.
SAMUEL WIDMER.
